Attorney

UNITED STATES PATENT OFFICE

MINNIE HOUSH, OF GALESBURG, ILLINOIS

KNITTING-NEEDLE HOLDER

Application filed October 8, 1928, Serial No. 311,154. Renewed June 9, 1930.

The present invention relates to improvements in knitting needle holders and the same pertains more particularly to means whereby a needle of the type at present employed on a knitting machine may be firmly held in the hand, for manually repairing knitted materials.

This invention is especially adaptable in conjunction with knitting needles of the type consisting of the hooked thread engaging end and the shank portion of the needle provided with a laterally disposed portion adjacent the free end of said shank, and which is engageable with the mechanism of certain types of knitting machines for properly securing the needle in place.

The prime object of the invention provides a holder for knitting needles of this type whereby a pair of such needles may be firmly held together during the alternate use thereof, in repairing hosiery, and in fact all sorts of knitted fabrics.

After considering the following specification and claims, numerous other objects and advantages of this novel holder will readily become apparent.

In the drawings:—

Figure 1 represents a side elevation of the holder with a pair of needles attached therewith.

Fig. 2 is an enlarged cross sectional view of the holder and needle taken substantially on the line 2—2 of Fig. 1.

Fig. 3 represents a top plan view of the holder and needles in association therewith in a somewhat different manner, and

Fig. 4 is a side elevation of the modified arrangement.

Referring to the drawings wherein like numerals designate like parts, needles such as are shown in the drawings, are especially adapted for use in conjunction with this improved holder, however, it is to be understood that any needle of similar construction may be employed with the same results.

The type of needle shown in the drawings consists of a body 1, having a fine hook 2 at one end thereof. A pivotal finger 3 has its free end engageable over the end of the hook 50 in substantially the manner clearly shown in

Fig. 1. The body 1 is provided with a shank portion 4 which is bent laterally at 5 and then backwardly to provide a longitudinal section 6 which is bent upon itself at 7 to provide a structure particularly adaptable for use in securing the needle to the type of knitting machine for which the same was designed.

In carrying out the invention, a tubing 8 of some suitable resilient material is employed, thru which the pair of needles of the aforementioned type may be inserted. These needles may be inserted through the tubing on an opposite direction, so that by forcing the needles a sufficient distance, the laterally disposed portions 5 of the said pair of needles will abut the ends of the tubing.

The bore through the tubing is to be of such cross sectional area as to the shank portions of the needles to bind therein.

Obviously, the hooked ends of the needles may be inserted through the same end of the tubing so that they will project beyond the opposite end thereof in substantially the manner shown in Figs. 3 and 4 respectively.

The use of a pair of needles of different sizes is preferable, as the mesh of various fabric articles frequently vary in gage. It also may be desired to engage the needles through the tubing 8 in the manner shown in Figures 3 and 4, this arrangement being more convenient when working on a fabric material of uniform mesh.

It will thus be seen that the present invention pertains to a simple means but an economical implement whereby a person may quickly become skilled in the repair of hosiery or other fabrics, wherein "runs" will have occurred.

Having thus described my invention, what I claim as new is:—

1. In a holder for knitting needles wherein the needles are each constructed with a shank portion having a laterally disposed end portion, a tube of resilient material through which the needles are to be inserted, and frictionally held, said needles being insertible through said tube from opposite directions, so that said laterally disposed end portion will abut the ends of the tube.

2. A knitting device comprising a pair of needles, each needle being provided with an enlargement at one end, a resilient tubing, said needles being adapted for frictionally retained disposition through said tubing with their enlarged ends abutting the opposite ends of the tubing.

3. A knitting device comprising a pair of needles of different sizes, each needle being provided with an enlarged end, a resilient tubing, said needles being adapted for disposition through said tubing so that their enlarged ends will abut one end of the tubing.

In testimony whereof I affix my signature.
MINNIE HOUSH.
